UNITED STATES PATENT OFFICE.

CHARLES DUCAS, OF NEW YORK, N. Y.

CENTRIFUGAL COMPRESSOR.

Application filed May 4, 1926. Serial No. 106,702.

My present invention relates to an improvement in centrifugal compressors, of the type in which, through the action of a centrifugal rotor, and the use of a fluid, as a compressor element therefor, gases may be readily compressed and stored until required.

One of the main features of the present invention relates to the manner in which the two active elements, the compressive, and the one to be compressed, are kept separate from each other and are brought together at a predetermined point within the system whereby the gaseous element is compressed by the compressor element which is introduced within the circuit for a short period of time and both elements thereafter automatically separated.

One particular advantage of this form of construction permits the segregation of the compressor element so that only part of it is in circuit during compression of the compressive element.

Another advantage of my present construction relates to the simplicity and compactness of the structural features involved, thereby creating a greater efficiency of operation and economy of construction.

Another object of the invention is the provision of a compressor of the character described having mercury as the compressor element.

Another object of the invention is the provision of a compressor of the character described having a continuously maintained column of mercury as the compressor element.

Another object is the provision of a compressor of the character described having a rotor provided with a rotor chamber kept under a head of mercury which provides the compression element, this chamber during rotation of the rotor being filled with the mercury and automatically maintained filled therewith after the compressor has been primed with mercury.

Other objects will appear as the description of the invention proceeds, and while herein details of the invention are described the invention is not limited to these, since many and various changes may be made without departing from the spirit of the invention or exceeding the scope of the appended claims.

Referring to the accompanying drawings forming part of the specification and show-

ing by way of example one of the possible embodiments of the invention,

Fig. 1 is a sectional elevation of the centrifugal unit and its drive means, the casing 60 of the unit being broken away at about a line 2-2 of Fig. 2, looking in the direction of the arrows,

Fig. 2 is a side elevation of the centrifugal pump unit with one side plate removed, and 65

Fig. 3 is a more or less diagrammatic view partly in section for convenience, outlining the coacting elements and circuit.

Similar reference characters denote similar parts throughout the several views. 70

In the structure herein disclosed, Fig. 2, the centrifugal pump unit is shown as comprising a casing made up of two parts, 1 and 2, the part 2 in Fig. 2 being removed so as to show the structural features of the rotor 75 generally denoted by 3.

The rotor 3 is a disk-like member mounted upon a pair of trunnions 4 and 5 supported in suitably mounted bearings 6 and 7 which are preferably integral to the housing members 2 and 1 respectively. 80

It will be noted by referring to Fig. 1 that the rotor 3 is preferably of a semi-cylindrical form at its edge in cross sections as at X and that the interior of the housing 1-2 85 conforms to this construction. It is intended that this rotor shall be a close fit within the housing with a minimum of clearness therebetween so as to eliminate friction and to prevent fluid losses during operation. 90

By referring again to Fig. 2 it will be ascertained that the disk 3 has a part of its periphery cut away leaving a chamber 8 formed between the housing and the flat peripheral surface 9 of the rotor. This cut 95 away portion terminates in a substantially flat pair of faces 10 and 11 and in practice preferably the cut away portion will occupy about one half of the peripheral diameter of the rotor. The surface 9 developed by the 100 cutting away of this portion will be preferably left flat.

One of the trunnions supporting the rotor, such as 4, is provided with an open port 12 therein which open port is carried to the 105 center of the rotor as at Fig. 1 and with an easy curve 13 passed upwardly as at 14, Figs. 1 and 2 and with another easy curve as 15 points up into the chamber 8 in a forward direction, this being indicated by the arrow 110 16.

At some predetermined point, a divertive

port 17 is provided which may be formed upon one of the casing members 1 or 2 and the outer end of the port part is provided with threads 18 so that connections may be affixed thereto as desired.

The opposite trunnion 5 of the rotor passes out from the rotor and by means of any suitable flexible coupling 19 is connected to an electric motor M or other type of motor 10 which is suitably mounted upon a base B which in turn is mounted on a common base plate P which supports both the centrifugal pump casing and the motor in driving alignment one with the other.

Both of the trunnions 4 and 5 are provided with stuffing box connections 20 and 21 respectively whereby to make these points leak-proof ends, without loss of the compressive element during use, and the stuffing box 20 may be so developed as to have an inner duct 21^a, having a threaded under portion 22 thereon for the purpose of receiving suitable attaching means thereon as desired.

A number of constructive variations may 25 be made upon the details of connections herein shown.

In Fig. 3 there is shown a diagrammatic outline of the proposed complete construction of my device in which like parts relating to the rotor are numbered as in Figs. 1 30 and 2 and in which view one of the rotor housings is removed in order to show the rotor itself in full lines.

Before attempting to describe the action 35 of the circuit generally shown in Fig. 3, it should be stated that it is my intention to use mercury as a compressor element in this pump and that during the action of the device and when it is fully primed for compression there is sufficient mercury carried 40 in the pump to fill the centrifugal chamber 8 with mercury, the duct 14, the orifice 4 and certain connections which will hereinafter be described so that, at all times, the rotor 45 chamber and its appurtenant parts are kept under a head of mercury so that during rotation of the rotor the chamber 8 is always filled with mercury and kept fully supplied 50 automatically after the system has been primed to a predetermined extent.

In order to complete the construction of 55 my circuit, by referring to Fig. 3 it will be ascertained that upon the threaded duct 18 there is connected any suitable form of coupler 23 which in turn is attached to the duct 24 which has preferably an easy bend 25 therein and this duct 24 in turn passes inwardly into and is received and supported by any suitable form of closure means such as a 60 spud 26 which is attached to an enclosed preferably metallic gas receiving chamber generally denoted by 27.

The duct 24 at a rotary point of the chamber 65 27 is tapered as at 28 whereby the stream of mercury issuing therefrom may be con-

strained but its velocity greatly increased at any given speeds of rotation of the rotor 3.

Surrounding the tapering jet nozzle 28 is a coacting tapering or funnel-like tubular member 29 which is open at 30 forming the 70 ingress for gas during compression and this in turn is connected to a duct generally denoted by 31 which is also supported firmly and rigidly and in an airtight manner to the gas container 27 by means of another 75 spud or similar element 32.

The duct 31 has in the present instance a bend 33 and extends down through spuds 34 which are attached to a compression chamber, generally denoted by 35 in 80 a gastight manner. The lower end of the duct 31 within the chamber 35 terminates in a short length 36 which is open at its bottom end. It in turn is surrounded by a flaring funnel-like coacting member 37 which 85 may be part of a tubular duct 38 which passes gastight spuds 39 and after turning in an easy bend 40 extends over to and is connected to the threaded end 22 of the stuffing box connection 21. The gas holding 90 compression chamber 35 is provided at one portion thereof with a valved, manually closable duct generally denoted by 41 which duct passes into and is joined to the wall of the funnel member 37 so that through this 95 connection, the end valve 42 may be opened and the entire system primed with mercury so that the system may be filled with mercury up to a level indicated by the lines A—C, Fig. 3, this level carrying out a somewhat higher point than any part of the rotor thereby insuring a solid column of mercury within the rotor and its previously described ducts and whereby a constant level of such mercury is being maintained within the 100 rotator during the operation. After priming as above described, the valve 42 is closed.

The compression gas tank 35 is also provided with an outlying duct generally shown as at 43 and is connected to a tank not 110 shown, in a gastight manner so that when gas is being compressed and received in tank 35 it may escape at predetermined compression through the duct 43 thereof to be utilized in any desired manner.

The gas tank 27 is also provided with a gas inlet duct generally denoted by 44 which is affixed to the tank 27 in a gas tight manner and whereby gas may be let in to be acted upon and be compressed as will now be described.

With the rotor 3, the duct 38 and the funnel 115 37 primed to the level herein outlined, the motor M is caused to rotate thereby driving the rotor 3 in the direction of the 120 arrow 16^a.

This rotation carries with it the mercury mass that has been spread in the chamber 8 and this mass is caused to rotate within the 125 rotor casing and when the rotor has reached 130

predetermined speeds, it is obvious that the mercury will exert a considerable centrifugal force due to said rotation and will tend to escape.

5 The mercury escapes and passes through the duct 17 to the duct 24 where it passes outwardly through the jet nozzle 28 and into the entrance to the duct 31 and this action of the mercury will cause an aspiration to 10 take place within the enclosed inlet chamber 27 and, gas being separated through the duct 44 such gas will be drawn into and through the coaxing jet member 29 and will be driven forwardly by the mercury, and depending 15 upon its velocity and the constraint exercised upon the outlying duct 43, the gas is forced into the container 35 under pressure and will there remain until released for use. A suitable pressure gauge indicated by G may be 20 provided for the container 35.

The combined mercury and gas stream passing through the duct 31 passes downwardly through the duct 36 and the mercury flows downwardly through the duct 38 and 25 continues to keep up with the head or solid column of mercury therein, while the gas escapes upwardly and out through the coaxing jet nozzle member 37 and thereby fills the container 35 with gas under compression.

30 The return of mercury through the duct 38 flows back to the rotor in the direction of the arrow 45, Fig. 3, and passes through the duct 12 into the duct 14 of the rotor and from thence into the chamber 8, thereby 35 maintaining constant supply of mercury within the chamber 8 and upon which centrifugal force is exerted due to the high speed rotation thereof by being driven around by the rotation of the rotor 3.

40 It is obvious from the foregoing that energy is supplied within the mass of mercury in the chamber 8 and that due to the one-half construction of the chamber, the duct 17 is closed for a one-half revolution, thereby cutting off the flow of mercury, and is opened for another one-half of a revolution thereby permitting the escape of a certain proportion of mercury from the chamber 8 so that the mercury is forced through the duct 24 in an 45 impulsive and uninterrupted manner thereby to draw the gas content out of the container 27 and cause it to pass through the duct 31 into the container or compression tank 35.

What I claim and desire to protect by 50 Letters Patent is:

1. In combination, a housing having an outlet, a disk-form rotor in the housing having means for containing fluid compressor element, said means being brought into and 55 out of communication with said outlet by rotation of the rotor, and means for rotating the rotor for thereby intermittently projecting the compressor element from said means into said outlet.

60 2. In combination, a housing having an

outlet, a disk-form rotor in the housing having means for containing fluid compressor element, said means being brought into and out of communication with said outlet for periods of substantially equal duration by 70 rotation of the rotor, and means for rotating the rotor for thereby projecting the compressor element from said means into said outlet.

3. In combination, a housing having an outlet, a rotor in the housing having a chamber, said chamber being brought into and out of communication with said outlet by rotation of the rotor, mercury in said chamber, and means for rotating the rotor for 80 thereby intermittently projecting the mercury from said chamber into said outlet.

4. In combination, a housing having an outlet, a rotor in the housing and having means for containing fluid compressor element, said means communicating with said outlet by rotation of the rotor and normally out of communication with said outlet, means for primarily filling said containing means with the compressor element, means 90 for rotating the rotor for centrifugally projecting the compressor element from said containing means into said outlet, and means for automatically maintaining said containing means filled with the compressor element 95 after primary filling of said means.

5. In combination, a housing having an outlet, a rotor in the housing and having a chamber communicating with said outlet by rotation of the rotor and normally out of communication with said outlet, means for primarily filling said chamber with mercury, means for rotating the rotor for centrifugally projecting the mercury from said chamber into said outlet, and means for 100 automatically maintaining said chamber filled with the mercury after primary filling of said chamber.

6. In combination, a housing having an outlet, a rotor in the housing and having means for containing a fluid compressor element, said means communicating with said outlet by rotation of the rotor and normally out of communication with said outlet, means for primarily filling said containing 110 means with the compressor element, means for rotating the rotor for centrifugally projecting the compressor element from said containing means into said outlet, and means for automatically maintaining said containing means filled with the compressor element 115 after primary filling of said means, the last mentioned means including a primary filler member and means cooperating between said member and said containing 120 means and means cooperating between said outlet and the primary filler member.

7. In combination, a housing having an outlet, a rotor in the housing and having a chamber communicating with said outlet by 130

rotation of the rotor and normally out of communication with said outlet, means for primarily filling said chamber with mercury, means for rotating the rotor for centrifugally projecting the mercury from said chamber into said outlet, and means for automatically maintaining said chamber filled with the mercury after primary filling of said chamber, the last mentioned means including a primary filler member and a duct cooperating between said member and said chamber and ducts operatively connected to each other and cooperating between said outlet and the primary filler member.

8. In combination, a tank constituting a compression tank, a filler member in said tank, means for supplying fluid compressor element to said member, a housing having an outlet, a rotor in the housing and having means for containing the fluid compressor element, the last mentioned means communicating with the housing outlet by rotation of the rotor and normally out of communication with said outlet, means communicating between said filler member and said containing means, means for rotating the rotor for centrifugally projecting the compressor element from said containing means into the housing outlet, a second tank, means for supplying fluid to the second tank, means communicating between the housing outlet and the second tank and having means for constraining the compressor element passing through this means, a member in the second tank communicating with the interior of the tank for passage of fluid from the tank into said member, said constraining means being disposed in said member for discharging the compressor element into said member, and means communicating between the last mentioned member and said filler member.

9. In combination, a tank constituting a compression tank, a filler member in said tank, means for supplying mercury to said member, a housing having an outlet, a disk-form rotor in the housing and having a marginal chamber for containing mercury, said chamber communicating with the housing outlet by rotation of the rotor and normally out of communication with said outlet, a duct communicating between said filler member and said chamber, means for rotating the rotor for centrifugally projecting the mercury from said chamber into the housing outlet, a second tank, means for supplying gas to the second tank, a duct communicating with the housing outlet and having a tapered end portion for constraining the mercury passing through this duct, a member in the second tank having a flaring mouth for passage of gas from said tank into the mouth, said end portion being disposed in said mouth for discharging mercury into the mouth, and a duct communicating with the last mentioned member and

having an open end portion disposed in said filler member.

10. In a device of the character described, a rotor including a disk having a portion of its peripheral margin cut away for providing a chamber extending circumferentially of the disk for substantially one half the peripheral margin of the disk. 70

11. In a device of the character described, in combination, a rotor having a chamber for fluid, and means for receiving fluid from said chamber, said chamber communicating with said fluid receiving means during part of the rotation of the rotor for projecting the fluid from said chamber into said means and being out of fluid projecting communication with said means during part of the rotation of the rotor, the periods of projection of the fluid from said chamber into said fluid receiving means and non-projection of the fluid into said means during rotation of the rotor being of substantially equal duration. 80

12. In a device of the character described, in combination, a rotor including a disk having a portion of its peripheral margin cut away for providing a chamber extending circumferentially of the disk for substantially one-half the peripheral margin of the disk, and a housing for the rotor having an outlet, said chamber communicating with said outlet during substantially one-half of the rotation of said rotor and being out of communication with said outlet during the other half of the rotation of said rotor. 90

13. In a device of the character described, a rotor having a chamber and a duct passing through the rotor and communicating with said chamber and means forming a closed circuit with said duct for introducing fluid compressor element into the chamber. 105

14. In a device of the character described, a rotor having a chamber and provided with trunnions for supporting the rotor and having a duct passing through one of the trunnions and through the rotor and communicating with said chamber and means forming a closed circuit with said duct for introducing fluid compressor element into the chamber. 110

15. In a device of the character described, a rotor having a cut away portion providing a chamber and a duct passing through the remaining portion of the disk and communicating with said chamber and means forming a closed circuit with said duct for introducing fluid compressor element into the chamber. 120

16. In a device of the character described, a rotor provided with trunnions for supporting the rotor and having a cut away portion of the rotor forming a chamber and a duct passing through one of the trunnions and through the remaining portion of 125

the disk adjoining said cut away portion and communicating with said chamber and means forming a closed circuit with said duct for introducing fluid compressor element into the chamber.

17. In combination, a rotor of disk-form having means for containing fluid compressor element, and a housing conformably enclosing the rotor and having an outlet extending tangentially to the periphery of the rotor, said containing means communicating with said outlet for centrifugally projecting the compressor element from said containing means into said outlet by rotation of the 10 rotor and being normally out of communication with said outlet.

18. In combination, a rotor of disk-form having means for containing fluid compressor element, means passing through a portion of the rotor and communicating with said containing means for introducing fluid compressor element into said containing means, and a housing conformably enclosing the rotor and having an outlet extending 20 tangentially to the periphery of the rotor, said containing means communicating with said outlet for centrifugally projecting the compressor element from said containing means into said outlet by rotation 25 of the rotor and being normally out of communication with said outlet.

19. In combination, a rotor of disk-form having trunnions and means for containing fluid compressor element, a housing conformably enclosing the rotor and having bearings for said trunnions and an outlet extending tangentially to the periphery of the rotor, and means passing through one 35 of said trunnions and through a portion of the rotor and communicating with said containing means for introducing fluid compressor element into said containing means, said containing means communicating with said outlet for centrifugally projecting the 40 compressor element from said containing means into said outlet by rotation of the rotor and being normally out of communication with said outlet.

20. In combination, a rotor of disk-form 50 having a cut-away portion of the disk forming a chamber, a duct passing through the remaining portion of the disk adjoining said cut away portion and communicating with said chamber for introducing mercury into the chamber, and a housing conformably enclosing the rotor and having an outlet extending tangentially to the periphery of the rotor, said chamber communicating with said outlet for centrifugally projecting mercury from the chamber into said outlet by rotation of the 55 rotor and being normally out of communication with said outlet.

21. In combination, a rotor of disk-form 60 having trunnions and having a cut away

portion of the disk forming a chamber, a housing conformably enclosing the rotor and having bearings for said trunnions and an outlet extending tangentially to the periphery of the rotor, and a duct passing 70 through one of said trunnions and through the remaining portion of the disk adjoining said cut away portion and communicating with said chamber for introducing mercury into the chamber, said chamber communicating with said outlet for centrifugally projecting mercury from the chamber into said outlet by rotation of the rotor and being normally out of communication with said outlet.

22. The combination with a rotor having fluid compressor element therein and adapted for intermittently projecting the fluid compressor element into an outlet means, of a tank having fluid therein, a duct communicating at one of its ends with said outlet means for receiving the compressor element therefrom, and a member in said tank for receiving fluid from the tank, the end of said duct opposite the first 90 mentioned end being disposed in said member for discharging the compressor element into said member and thereby drawing by entrainment into said member fluid from the tank.

23. The combination, with a rotor having mercury therein and adapted for projecting the mercury into an outlet means, of a tank having gas therein, a duct communicating at one end of its ends with said outlet means for receiving mercury therefrom and having at its opposite end a tapered portion for constraining and discharging the mercury, a member in said tank having a mouth for receiving gas from the tank, said tapered end portion being disposed in said mouth for discharging mercury therein and thereby drawing by entrainment into said member gas from the tank, a second tank constituting a compression tank, a filler member in the second tank and having a flaring mouth, a duct communicating at one of its ends with said member of the first tank for receiving mercury and gas from this member and having its opposite end disposed in the mouth of the filler member for discharging the gas and mercury into the filler whereby the gas and mercury are separated, the gas rising in the second tank and the mercury being deposited in the 100 filler member, and a duct communicating between the filler member and the rotor for maintaining a constant column of mercury between the filler member and the rotor.

24. In combination, means for providing a constant flow of fluid compressor element, means for intermittently discharging the compressor element, means for controlling the flow of said intermittently discharged compressor element, means for introducing 125

a fluid into the path of intermittent flow of the compressor element after its aforementioned discharge, a compression means, means for discharging said fluid and compressor element into said compression means and separating the fluid from the compressor element for compression of the fluid, and means for returning the compressor element to said compressor element providing means.

25. In combination; means for supplying a constant stream of mercury to a receiving means adapted for discharging the mercury therefrom at predetermined intervals, means for introducing gas into the path of the discharged mercury so that the gas is drawn along by entrainment of the mercury, a compression tank, means for passage of the mercury and gas into said tank, and means for separation of the gas from the mercury for compression of the gas and return of the separated mercury to said means for supplying a constant stream of mercury.

26. In combination; a rotor having a chamber for receiving mercury and adapted for discharging the mercury at predetermined intervals, means for supplying a constant column of mercury to said receiving means, means for introducing gas into the path of the mercury discharged from said rotor so that the gas is drawn along by entrainment of the mercury, a compression tank, means for passage of the mercury and entrained gas into said tank, and means appurtenant to said tank for separating the gas from the mercury for compression of the gas and return of the separated mercury to said means for supplying a constant column of mercury.

40. 27. In combination, a rotor including a rotatable disk having in its peripheral margin a chamber extending circumferentially of said margin for substantially one-half the circumference of the disk, a housing around said disk having an outlet from the housing,

said chamber communicating with said outlet during substantially one-half the rotation of the disk and being out of communication with said outlet during the other half of the rotation of the disk, a duct for supplying a constant column of mercury to said chamber, means for rotating said rotor, a tank, means for supplying gas, a second duct cooperating between the outlet of the housing and said tank for passage to the tank of the mercury discharged from said chamber into said outlet by rotation of the rotor, said second duct having a constricted discharge end located in said tank, a compression tank, a third duct cooperating between the first tank and the compression tank and having at one of its ends a flaring mouth disposed in the first tank around said discharge end whereby gas is drawn from said means of gas supply into the first tank and thence into the third duct by entrainment of the mercury discharged from said discharge end, the third duct having at its other end a straight discharge end located in the compression tank, and a member in the compression tank having a flaring mouth disposed around said straight discharge end and having a straight stem portion cooperating between said mouth and the first duct.

28. In a device of the character described, a disk-form rotor having a chamber on a portion of its peripheral margin, and means forming a closed circuit with said chamber for conducting compressor fluid to said chamber.

29. In a device of the character described, a disk-form rotor having a cut away portion providing a chamber extending circumferentially of the disk, and means forming a closed circuit with said chamber for conducting compressor fluid to said chamber.

Signed at New York in the county of New York and State of New York this 3rd day of May A. D. 1926.

CHARLES DUCAS.
